Primary Examiner — Darlington Ly(74) *Attorney, Agent, or Firm* — Grandview Law(57) **CLAIM**

The ornamental design for a grinding bit for rotary tool, as shown and described.

DESCRIPTION

FIG. 1 is a top and side perspective view of a grinding bit for rotary tool showing my new design;

FIG. 2 is a top plan view thereof;

FIG. 3 is a side elevation view thereof;

FIG. 4 is a cross-sectional view thereof, as taken along line 4-4 in FIG. 3; and,

FIG. 5 is a bottom plan view thereof.

The features shown in broken lines in the drawing figures depict features that form no part of the claimed design.
